ABSTRACT OF THE DISCLOSURE

An outer form for use in annealing wound type transformer cores. The form is an integral one-piece open rectangular frame adapted to receive a core such that the core yokes or shorter core legs are restrained against outward movement by the frame during annealing and the longer core legs are restrained by stacking of the core and form assemblies in an annealing oven.

BACKGROUND OF THE INVENTION

This invention pertains to an annealing form and methods for producing transformer cores, and particularly to an outer form for use in annealing wound transformer cores.

In the art of producing transformers, and particularly distribution transformer, the cores thereof are usually formed by winding a strip or strip segments of grain oriented magnetizable material into a generally circular configuration. Such wound cores are provided with openable joints by one of several methods and are die-formed from their circular configuration to a generally rectangular configuration with a central opening or window. The thus formed cores are then annealed in a suitable annealing furnace to eliminate the stresses set up in the cores during the winding and die-forming operations, which stresses adversely affect the magnetic properties thereof. After annealing, the cores are assembled with preformed coil units by opening them at their joints, inserting them through the coil center openings, and reclosing their joints. The assembled core and coil units are then mounted by suitable frames in tanks.

Outwardly directed forces are present in the core winding both prior to and during annealing due to the tendency of the core material to relax and return to its unpressed circular configuration. These forces tend to bow the yoke and leg portions of the core outwardly and cause the core to assume a generally oval or football configuration. This, of course, is undesirable since the overall core and window configuration is changed from the desired rectangular shape having predictable dimensions to a somewhat oblong shape having unpredictable dimensions, thereby increasing the difficulty of lacing or assembling the core around a preformed coil unit and causing a substantial number of rejects due to the inability of the core to be properly assembled with a preformed frame. To overcome this problem during the annealing operation, the prior art typically utilized either a plurality of band straps encircling the core legs and yokes, or four rigid plates secured around the periphery of the core by a plurality of straps or bars. Such devices have not proven satisfactory, however, since they are time consuming to assemble around a core, the band straps frequently break under the expansive loads produced during annealing, and the plates and straps are unwieldy and difficult to use.

SUMMARY OF THE INVENTION

Among the several objects of the present invention may be noted the provision of an outer form for wound transformer cores which securely restrains the cores

2

against outward movement during annealing and permits the cores to be mounted within the tank by preformed frames; the provision of such a form in which a core may be easily inserted and which permits an inner annealing form to be inserted in the core window either before or after assembly with the outer form; the provision of such a form which securely restrains the inner form against rotation in the outer form; and the provision of such a form which may be utilized with cores of different sizes. In addition, the present annealing form is characterized by simplicity of construction, low cost and ease of use. Other objects and features will be in part apparent and in part pointed out hereinafter.

Briefly, an outer annealing form of this invention is comprised of an integral one-piece open rectangular frame having a pair of flat end plates held in spaced substantial parallel relationship by a pair of side plates, one of the side plates having a center opening of sufficient dimension for the passage of an inner annealing form. The method of this invention for annealing transformer cores having a pair of legs, a pair of yokes and an open center window includes the steps of inserting the core in an outer annealing form comprised of an open rectangular frame having a pair of plates for restraining the core yokes against outward movement during annealing. A plurality of assembled core and form units are then stacked with the legs of each core in vertical alignment so that the weight of the stack above a respective core biases the legs of that core toward each other and restrains the legs against outward movement during annealing. The stacked assembled core and form units are then heated.

BRIEF DESCRIPTION OF THE DRAWINGS

FIG. 1 is a perspective view of an outer annealing form of the present invention;

FIG. 2 is a perspective view of a wound die-formed transformer core;

FIG. 3 is a side elevation of the form of FIG. 1 with a transformer core positioned therein;

FIG. 4 is a plan view similar to FIG. 3; and

FIG. 5 is a side elevation illustrating a pair of core and form assemblies stacked in an annealing furnace.

Corresponding reference characters indicate corresponding parts throughout the several views of the drawings.

DESCRIPTION OF THE PREFERRED EMBODIMENT

Referring now to the drawings, and particularly to FIG. 1, the present outer annealing form is indicated generally at 1. The form is constituted by an integral one-piece cast assembly defining an open rectangular frame having a pair of flat end plates 3 and 5 held in spaced parallel relationship by first and second side plates 7 and 9, respectively. The first side plate 7 is constituted by a pair of elongate bars 11 and 13 of generally rectangular cross-sectional configuration disposed between the upper corners of the end plates 3 and 5. Bars 11 and 13 define a center opening 15, also of generally rectangular configuration, of sufficient dimension for the passage of an inside or inner annealing form 17 (see FIG. 3). The second side plate 9 is similarly constituted by a pair of elongate bars 19 and 21 disposed between the lower corners of end plates 3 and 5. A generally rectangular opening 23 is also provided between bars 19 and 21, and a cross-plate 25 spans the opening and connects the bars at their centers. As illustrated in FIGS. 1 and 4, the cross-plate 25 is recessed below the inside or upper surface of bars 19 and 21, the purpose of which will become apparent hereinafter. A reinforcing web 27 and 29 is provided at each of the ends 3 and 5 of the annealing form for increasing its end-to-end strength. The webs 27 and 29 are of generally

T-shaped cross-sectional configuration (see FIG. 3) having head portions 31 and shank portions 33, the head portions tapering inwardly at 35 from a maximum width adjacent the end plates to a minimum width over the center of the end plates. As clearly illustrated in FIG. 1, the top and bottom of the annealing form defined by the areas between end plates 3 and 5 and bars 11, 19 and 13, 21 are open.

A typical wound die-formed transformer core is illustrated in FIG. 2 at 37. The core is constituted by a plurality of superposed turns of grain oriented magnetic strip material die-formed into a generally rectangular configuration having leg portions 39 and 41 and yoke portions 43 and 45. A center generally rectangular window 47 is provided between the leg and yoke portions of the core and a series of openable joints 46 are provided in leg 39 for permitting the core to be opened after annealing for assembly with a preformed coil unit.

Referring to FIGS. 3 and 4, outer annealing form 1 is applied to the core 37 after it has been formed into the configuration shown in FIG. 2, and before it is placed in the annealing furnace. To accomplish this, core 37 is placed flat on a table or suitable support such that legs 39 and 41 lie in a horizontal plane. The outer form 1 is then lifted by end webs 27 and 29, positioned above the core 37 and slipped downwardly over the core, the latter passing through either the open top or bottom of the form. In this position, it should be noted that legs 39 and 41 of the core project outwardly from the open top and bottom of the form past bars 11, 19 and 13, 21, and yokes 43 and 45 engage end plates 3 and 5, respectively. The assembled form and core unit is then rotated 90° on the support such that it rests on bars 19 and 21, and inner annealing form 17 is forced through the opening 15 and into core window 47. The inner core form 17 is forced downwardly through window 47 until it abuts cross-plate 25 spanning bars 19 and 21. In this position, the lower edges of the longer legs of form 17 abut the perimeter of lower opening 23 thereby holding form 17 parallel to bars 19, 21 and 11, 13 and preventing the core from rotating in the outer form. It may be desirable to restrain core legs 39 and 41 by means of a band strap 49 encircling the core girth and secured by a clamp 51.

When a plurality of core and form units have been assembled, they are stacked in an annealing furnace with the legs of each core in vertical alignment so that the weight of the stack above each core acts to bias the legs thereof toward each other, thus restraining core legs 39 and 41 against outward movement. As illustrated in FIG. 5, a pair of assembled core and form units are stacked in an annealing furnace 53 with the windings of core legs 39 and 41 horizontal. The lower unit lies upon a heavy steel plate 55 and the units are separated by a sheet of heavy gauge screen or expanded metal 57. A similar plate 59 overlies the upper unit and several additional pairs of units and plates (not shown) are stacked in a similar manner. The uppermost plate in the stack may be weighted to provide sufficient biasing to provide restraint for the legs of the uppermost cores. Thus, the weight of the stack above a respective core effectively restrains legs 39 and 41 of such core 37 from outward movement during the annealing operation, and the outer form 1 restrains outward movement of the yoke portions 43 and 45. Inner form 17 maintains the core window 47 rectangular during annealing, and this form may be inserted in the core prior to inserting the core into the outer form, rather than after as described above.

It should be noted that each of the present outer annealing forms may be utilized with several cores of different sizes by the use of one or more shims inserted between one of the core yokes and the corresponding end plate of the form. Thus, for example, only four different form sizes and eight shims are necessary to anneal cores from 8 1/4 to 14 1/4 inches in length for transformers of from 5 to 50 kva.

The outer annealing form of this invention, therefore, securely restrains transformer cores against outward movement during annealing, thereby holding the dimensions of these cores to close tolerances and permitting the cores to be utilized with preformed frames of predetermined sizes.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

15 What is claimed is:

1. An outer annealing form for wound transformer cores, said form comprising an integral one-piece open rectangular frame having a pair of flat end plates held in spaced substantially parallel relationship by a pair of side plates, each side plate comprising two bars of substantially rectangular cross-section extending between respective corners of the opposed end plates, one of said side plates having a center opening of sufficient dimension for the passage of an inner annealing form, and a cross-plate spanning the bars opposite the center opening, said cross-plate being recessed from the inside surfaces of said bars for holding an inner annealing form against rotation in said outer annealing form.

2. An annealing form as set forth in claim 1 further comprising a reinforcing web on the outside of each of said end plates, said webs having a generally T-shaped cross-section.

3. A method of annealing wound transformer cores of generally rectangular configuration having a pair of leg and a pair of yoke portions with an open center window therebetween, comprising the steps of inserting the core in an outer annealing form comprised of an open rectangular frame having a first pair of plates for restraining the core yokes against outward movement during annealing, stacking a plurality of assembled core and form units with the leg portions of each core in vertical alignment so that the weight of the stack above a respective core biases the legs of that core toward each other and restrains the legs against outward movement during annealing, and heating the stacked assembled core and form units.

4. The method of claim 3 wherein said first pair of plates are held in spaced substantially parallel relationship by a second pair of plates, one of said second plates having a center opening, and further comprising the steps of inserting an inner annealing form through said opening into said core window, and restraining said inner form against rotation in said outer form.

5. A method of annealing wound transformer cores of generally rectangular configuration having a pair of leg and a pair of yoke portions with a window therebetween, comprising the steps of inserting the core in an outer annealing form comprised of an open rectangular frame having a first pair of flat plates held in spaced substantially parallel relationship by a second pair of plates, said second plates each having a center opening therein, one of which is spanned by a recessed cross-plate, said first plates restraining the core yokes against outward movement during annealing, inserting an inner annealing form through said opening in one of said second plates and into the core window until it abuts the cross-plate, restraining said inner form against rotation in said outer form by engagement thereof with the periphery of the opening spanned by said recessed cross-plate, stacking a plurality of assembled core and form units with the legs of each core in vertical alignment so that the weight of the stack above a respective core biases the legs of that core toward each other, thereby restraining the core legs against outward movement during annealing, and heating the stack at a predetermined temperature for a predetermined period of time.

70

6. An outer annealing form for wound transformer cores, said form comprising an integral one-piece open rectangular frame having a pair of flat end plates held in spaced substantially parallel relationship by a pair of side plates, each side plate comprising two bars of substantially rectangular cross-section extending between respective corners of the opposed end plates, one of said side plates having a center opening of sufficient dimension

for the passage of an inner annealing form, and a cross-plate spanning the bars opposite the center opening.
